UNITED STATES PATENT OFFICE

JOSEPH WINTER, OF ERIE, PENNSYLVANIA

SPICE RACK

Application filed June 3, 1929. Serial No. 368,082.

The present invention contemplates the provision of an article supporting rack, primarily intended for use in households and the like, and on which a large number of articles such as spice cans and the like varying in size and shape can be conveniently supported, and in a manner to permit any particular article to be quickly removed from the rack and again associated therewith as the occasion 10 may require.

The nature and advantages of the invention will be better understood when the following detail description is read in connection with the accompanying drawings, the 15 invention residing in the construction, combination and arrangement of parts as claimed.

In the drawings forming part of this application like numerals of reference indicate 20 similar parts in the several views, and wherein:

Figure 1 is a front elevation of a rack constructed in accordance with the present invention.

Figure 2 is a side elevation partly in section of a slightly modified construction.

Figure 3 is an enlarged fragmentary view of the rack shown in Figure 1.

Referring to the drawings in detail, and 30 more particularly to Figures 1 and 3 inclusive, the rack is formed from a single blank of material, preferably of metal and may vary in size without departing from the inventive idea. The rack is formed with means 35 for supporting containers and the like indicated at 10 in spaced vertical rows as shown in Figure 1, irrespective of whether the container is cylindrical in shape or of rectangular contour in cross section, and also independently of the particular size of the container to be supported.

The means for this purpose is stamped from the body 11 of the rack proper, which as above stated is in the nature of a sheet of 45 metal or other suitable material, and as clearly illustrated in Figure 3, this means for each container embodies a pair of resilient jaws 12 projecting outwardly from the body 13 of the rack and directly above a shelf 13 50 which also projects laterally from the rack.

The container is arranged upon the shelf 13 and is embraced by the resilient jaws 12 as clearly illustrated in Figure 1. Some of the shelves are designed to accommodate cans of cylindrical contour, while as shown in Figure 3 some of the shelves are shaped to support a container of rectangular contour in cross section, and it is manifest that the shape of the shelf for a particular type of container can be varied at will without departing from the scope of the invention. 55 However, for each shelf 13 the rack is provided with a pair of resilient jaws 12, and these jaws can be spaced apart different distances to accommodate containers of different sizes. It will be further noted upon inspection of Figure 3 that each shelf is crimped to provide a bead 14 which fits in the recess usually formed at the bottom of spice containers and the like, and thereby assist the 60 jaws 12 in holding the container properly positioned upon the rack. Its bead may be of semi-circular contour or extended straight across the shelf, depending upon the shape of the particular container to be supported 65 thereon.

The spring jaws 12 may be arranged directly opposite each other as shown on the right hand side of Figure 3, or they may be arranged as illustrated at the left of Figure 80 3, that is the jaws of each pair may be arranged one above the other, but in close proximity to each other to partly embrace the receptacle as shown in Figure 1.

Each shelf 13 is also stamped to provide a 85 resilient tongue 15 which extends slightly beneath the shelf, so that when the containers are arranged upon the rack in column formation, the resilient tongue 15 of one shelf 90 rests against the top of the next lowermost 95 container, thereby exerting a slight downward pressure upon the container and holding it properly positioned upon its shelf. If desired the entire rack may be crimped or pressed to provide the same with reinforcing 100 ridges about the marginal edges thereof, as at 16 and also between each column of containers as at 17.

In Figure 2 I have shown the invention as hereinabove described, except that the rack 100

may be provided with a hinged cover or front wall 18 to conceal the containers from view, and which cover is supported from a horizontal ledge 19 projecting from the body of the rack adjacent the top thereof. Otherwise the construction in Figure 2 is the same as that described in connection with the first form of the invention.

While it is believed that from the foregoing description the nature and advantages of the invention will be readily apparent, I desire to have it known that I do not limit myself to what is herein shown and described, and that such changes may be resorted to when desired as fall within the scope of what is claimed.

What I claim is:

1. An article supporting rack of the character described comprising a substantially flat body member, means carried by the body member for supporting a plurality of articles in column like formation thereon, said means including a plurality of shelves stamped from the body member at a right angle thereto and arranged in spaced superimposed relation, means forming part of the body member and arranged above each shelf to assist in supporting the article thereon, and a resilient tongue stamped from each shelf and arranged to engage the next adjacent container to exert a slight downward pressure upon the latter for the purpose specified.

2. An article supporting rack of the character described comprising a substantially flat body member, means for supporting a plurality of articles in column like formation upon said member, said means including a plurality of shelves stamped from the body member and projecting at a right angle therefrom in spaced superimposed relation, a pair of spring jaws projecting from the body member above each shelf and adapted to embrace the article supported upon the latter, and a spring tongue stamped from each shelf and arranged to engage the next adjacent container to exert a downward pressure thereon for the purpose specified.

In testimony whereof I affix my signature.
JOSEPH WINTER.
